UNITED STATES PATENT OFFICE.

HENRY SMITH CUSHMAN, OF MILFORD, MASSACHUSETTS.

MANUFACTURE OF BOOT OR SHOE UPPERS.

SPECIFICATION forming part of Letters Patent No. 341,835, dated May 11, 1886.

Application filed March 8, 1886. Serial No. 194,417. (No model.)

To all whom it may concern:

Be it known that I, HENRY SMITH CUSHMAN, of Milford, in the county of Worcester, of the Commonwealth of Massachusetts, have 5 invented a new and useful Improvement in the Manufacture of Boot or Shoe Uppers; and I do hereby declare the same to be described in the following specification and represented in the accompanying drawings, of 10 which—

Figure 1 is a side view of a blank for the formation of a shoe-upper in accordance with my invention, the nature of which is defined in the claims hereinafter presented. Fig. 2 15 is a side view of a blank for the formation of a boot-upper embodying such invention. Figs. 3 and 4 are longitudinal sections of such blanks, showing the manner in which they are split to form them into uppers. 20 Figs. 5 and 6 are top or upper edge views, and Figs. 7 and 8 are lower edge views, of such blanks, showing the lines of separation of each in order to form it into an upper. Fig. 9 is a top view of the shoe-upper as made 25 from the form shown in Fig. 1.

In carrying out my invention I take a piece of leather of double the thickness required for the upper, and having a boundary of proper shape—that is, essentially as shown at 30 A in either of the Figs. 1 and 2—and I split it lengthwise, from its lower edge upward, to and through its upper edge, except that I do not slit it through its back or rear edge, nor through its front edge, except perhaps for 35 a shoe or bootee particularly.

In Figs. 5, 6, 7, and 8 of the drawings the slit is shown by the line a.

In Fig. 3 the contour of the blank is shown at b c d e f and that of the slit at g h i k l c g, 40 while in Fig. 4 the contour of the blank is represented at b c d e and that of the slit at f g h i.

By cutting or slitting the blank as shown in Fig. 3 it becomes separated, except at the 45 back and part of the front of it, it being open both at top and bottom and through part of its front.

By slitting the blank as shown in Fig. 4 it becomes separated, except at its back and 50 front, it being open both at top and bottom.

Having thus split the blank, it may be placed on a proper last or mold and have its connections at its front and back properly

rubbed down, after which the upper thus made may be lined, bound, or otherwise treated as 55 uppers usually are preparatory to being soled and finished.

I do not claim a shoe-upper split from leather in the manner as represented in either of the Patents Nos. 295,826, 320,406, or 50 303,883, it being open at its rear edge, and has to be "back-seamed" to complete it, whereas my upper has neither a back nor a front seam.

I claim—

1. As a new or improved manufacture, a 65 shoe-upper composed of a single piece of leather, in form substantially as represented, split lengthwise from its lower to its upper edge, excepting through and along its rear edge and part of its front edge, whereby the upper so made is without any back seam.

2. As a new or improved manufacture, a boot-upper composed of a single piece of 70 leather, in form substantially as represented, split lengthwise from bottom to top, excepting at its front and rear edges, as set forth, whereby such upper, when finished, has no front or back seam extending from top to bottom of it.

3. The process, substantially as described, 75 of manufacturing a shoe-upper, such process consisting of slitting a blank piece of leather of the required form, substantially as represented, lengthwise from its bottom to its top, except at its rear edge and part of its front edge, and subsequently stretching it upon a last and rubbing down or reducing the parts left uncut, so as to complete the upper without any back or front seam, all as set forth. 80

4. The process, substantially as described, 85 of manufacturing a boot-upper, such process consisting in slitting a blank piece of leather of the required form, substantially as represented, lengthwise from bottom to top, except through its front and rear edges, and subsequently stretching it on a proper last or form and rubbing down or reducing the parts left uncut, so as to complete the upper without any seam either at its front or back, all being es- 90

sentially as explained.

HENRY SMITH CUSHMAN.
